UNITED STATES PATENT OFFICE

GEORGE G. HARRINGTON, OF HOUSTON, TEXAS, ASSIGNOR TO REED ROLLER BIT COMPANY, OF HOUSTON, TEXAS, A CORPORATION OF TEXAS

BLOW-OUT PREVENTER

Application filed October 27, 1930. Serial No. 491,338.

This invention relates to blow out preventers.

In deep well drilling operations, it is customary to bore a hole in the earth with a drill, 5 lower a pipe casing into the hole, and then lower a drill through the casing to make the hole deeper, smaller pipe sections being added to the casing from time to time and made to occupy the extensions of the hole made by the 10 drill stem. For various reasons well known to those skilled in the art, it is frequently necessary to remove the drill stem from the casing.

High fluid pressures are frequently 15 encountered which cause a rush and escape of fluid upwardly through the casing and about the stem, while the stem is being removed from the casing. At times such pressures are sufficiently great to blow the drill stem out 20 of the casing, the disastrous consequences of which are well known.

To prevent the foregoing, this invention has for its general object the provision of a new and improved blow out preventer, 25 adapted to be quickly and easily applied to a drill stem to securely lock it in the casing should a blow out be threatened during its removal from the casing.

Other specific objects will hereinafter appear.

The preferred embodiment of the invention is illustrated by the accompanying drawings, of which Fig. 1 is a sectional elevation of the assembled elements taken on the line 35 1-1 of Fig. 3; Fig. 2, a side elevation of the locking sleeve; Fig. 3, a top plan view partly in section, taken on the line 3-3 of Fig. 1; Fig. 4, a top plan view of the locking sleeve open for application to a drill 40 stem; Fig. 5, a partly sectional elevation of those elements, other than the locking sleeve, assembled; and Fig. 6, a top plan view of the packing sleeve.

The bowl 1, mounted on the casing 2, has 45 internal interrupted threads 3 (Fig. 5). Mounted upon the side of the bowl, as indicated at 4, is the worm 5.

The drill stem 6 has a conventional tool joint or collar 7.

The packing sleeve 8 is diametrically split

into two sections having interlocking fingers 8a joined together by a pivotal pin 9, and interlocking fingers 8b joined together by the locking pin 10. This sleeve has in its upper end an internal, annular flange 8c projecting 55 upwardly and inwardly. In its lower portion, the sleeve has an internal annular flange 8d having therein a plurality of fluid ducts 8d'.

Between the flanges 8c and 8d is the annular diametrically split packing 11; and between the packing 11 and the flange 8d is the diametrically split floating ring 12. The lower end of the bowl 1 is reduced to form an internal annular shoulder upon which the 60 packing sleeve 8 rests; and a suitable gasket 13 may be employed to seal the space between the sleeve and the bowl.

The locking sleeve 14 is diametrically split into two sections having interlocking fingers 70 14a joined by a pivotal pin 15; and interlocking fingers 14b joined by a locking pin 16. This sleeve has external interrupted threads 14c to engage the internal interrupted 75 threads 3 of the bowl 1 and peripheral teeth 14d to be engaged by the worm 5. It also has in its lower end an internal annular flange 14e to rest upon the internal annular flange 8c of the sleeve 8.

It will be apparent from the foregoing that 80 should a blow out be threatened when the drill stem 6 is being removed from the casing 2, the packing sleeve 8 may be placed about and made to embrace the drill stem 6, and the locking pin 10 inserted. The packing sleeve 85 8 may then be dropped into the bowl 1, and the drill stem 6 lowered until the collar 7 rests upon the flange 8c. Fluid under pressure rising upwardly in the casing 2 about the drill stem 6 will pass through the ducts 90 8d' and force the floating ring 12 upwardly to compress the packing 11 and thereby seal the space between the sleeve and the drill stem to prevent the escape of the fluid.

If there is any danger of the fluid pressure 95 being sufficiently great to blow the drill stem 6 out of the casing 2, the locking sleeve 14 may then be made to embrace the drill stem, the locking pin 16 inserted, and said sleeve 100 dropped into the bowl 1 upon the sleeve 8.

The worm 5 may then be rotated to cause engagement of the external threads 14c of the sleeve 14 and the internal threads 3 of the bowl whereby the locking sleeve 14 and the packing sleeve 8 therebelow will be positively locked in the bowl. Should the drill stem be elevated by the fluid under pressure, its collar immediately below the bowl will be engaged by the flange 8d so that the drill stem 10 cannot be blown out of the casing.

Many advantages of an apparatus constructed in accordance with this invention will be apparent to those skilled in the art. Of these, attention is invited particularly to 15 the simplicity of the apparatus and the fact that it may be very quickly and easily installed in an emergency, and as easily removed.

The invention is not limited to the preferred embodiment shown. Various changes 20 may be made within the scope of the following claims.

I claim:

1. The combination with a casing having a 25 shoulder and a stem having a collar, of a substantially diametrically split packing sleeve having upper and lower internal annular flanges, said shoulder serving to support said sleeve, said upper flange to engage 30 said collar, said lower flange having a fluid duct therein, and a substantially diametrically split packing between said flanges to be compressed by fluid passing through said duct.

35 2. The combination with a casing having a shoulder and a stem having a collar, of a substantially diametrically split packing sleeve, the sections of said sleeve being pivoted together, said shoulder serving to support said sleeve, said sleeve having upper and lower internal annular flanges, said upper flange to engage said collar, said lower flange having a fluid duct therein, a substantially diametrically split packing between said flanges, and a substantially diametrically split floating ring adjacent said duct and movable by fluid passing therethrough to compress said packing.

3. The combination with a casing having 50 a shoulder and a stem having a collar, of packing means comprising a packing sleeve substantially diametrically split to be placed about said stem, to be supported by said shoulder, and to engage said collar, a substantially diametrically split packing within 55 said packing sleeve, and a substantially diametrically split locking sleeve to be placed about said stem and to hold said packing sleeve in said casing.

60 4. The combination of a casing and a stem having a collar, of a bowl mounted on said casing and having internal interrupted threads, a packing sleeve substantially diametrically split to be placed about said stem 65 and slipped into and out of said bowl, said

sleeve having an upper internal flange to engage said collar, and a lower internal flange with a fluid duct therein, a substantially diametrically split packing between said flanges, a floating ring adjacent said duct and movable by fluid passing therethrough to compress said packing, and a locking sleeve substantially diametrically split to be placed about said stem and having external interrupted threads to engage the internal interrupted threads of said bowl to hold said packing sleeve in said bowl.

5. The combination with a well casing having a shoulder and a stem having a collar, of a packing sleeve having upper and lower internal annular flanges, said shoulder serving to support said sleeve, said upper flange to engage said collar, said lower flange having a fluid duct therein, and a packing between said flanges to be compressed by fluid passing through said duct, said collar being supported by said sleeve independently of said packing.

In testimony whereof, I hereunto affix my signature.

GEORGE G. HARRINGTON.
